UNITED STATES PATENT OFFICE.

HALBERT R. BRADLEY, OF CHICAGO, ILLINOIS.

STEEL TRUSS.

Application filed January 14, 1922. Serial No. 529,121.

To all whom it may concern:

Be it known that I, HALBERT R. BRADLEY, a citizen of the United States, and resident of Chicago, in the county of Cook and State 5 of Illinois, have invented certain new and useful Improvements in Steel Trusses, of which the following is a specification.

This invention relates to steel trusses and relates particularly to steel trusses fabricated from commercially available steel sections, especially designed and adapted for supporting the roofs of relatively wide buildings—as the roofs of garages—in which an unobstructed floor space is desired.

At the present time, trusses for the purpose specified are generally made of wood and are relatively cheap, and in order that steel trusses may compete commercially with such wood trusses, it is necessary that they 20 shall be so designed that the weight of the metal contained therein and the cost of fabrication shall be reduced to a minimum, while, at the same time, providing requisite strength in the structure.

Also, buildings such as those in which my improved truss will be used most extensively, are lighted principally by means of skylights, and in order that the roof trusses shall obstruct the passage of light as little 30 as possible, it is desirable that the trusses shall consist of relatively few parts and that they shall be as small as possible, consistent with requisite strength.

Stated broadly, therefore, the object of 35 my invention is to provide a steel truss for the purposes specified, which can be manufactured at such small cost that it can compete commercially with the wooden trusses now generally used.

To effect the objects of the invention, my improved truss comprises a bowed top chord, a bottom chord comprising end sections which are upwardly and inwardly inclined relative to a right line connecting the ends 40 of the truss—hereinafter, for purposes of convenient reference, designated as the base line—and an intermediate section which extends parallel with said base line, and web members comprising two inclined members 45 at each end of the truss which connect the inner ends of the inclined bottom chord sections with the top chord, the points of connection of said inclined web members to said top chord being defined by the intersection therewith of the extreme four of at 50 least six lines—hereinafter designated ordi-

nates—projected upwardly from points in the base line of the truss which divide it into parts of equal length and the inner ends of the inclined bottom chord sections terminating substantially at the third ordinates from the outer ends of said inclined bottom chord sections, respectively, said web members also comprising upright members which connect the top and bottom chords, two of which 60 are substantially coincident with the third ordinates from the ends of the truss, and diagonal bracing members which connect the upper and lower ends, respectively, of adjacent upright web members.

My improved truss also comprises the various other features and details of construction hereinafter described and claimed.

In the accompanying drawing,

The figure is a side view of a truss embodying my invention and improvements.

Describing my improved truss with particular reference to the drawing, A designates the truss, as a whole, said truss comprising a bowed top chord 1, a bottom chord 75 comprising end sections 2, 2', which are inwardly and upwardly inclined to the base line of the truss, indicated by the dotted line 3, and an intermediate section 22 which extends parallel with said base line.

The inclination of the bottom chord sections 2, 2' to the base line of the truss is approximately eight (8) degrees and is constant for all trusses embodying my invention and improvements regardless of their 90 length.

In the preferable embodiment of my invention the curvature of the top chord 1 is ascertained and determined in the following manner: From at least six points in the base 95 line 3 which divide it into parts of equal length, lines 4, 4', 4², 4³, 4⁴, 4⁵ and 4⁶ are projected backwardly, said lines, for purposes of convenient reference being herein-after designated ordinates.

Reckoning from the base line, the height of the truss at the ordinates 4, 4⁶, is approximately twelve (12%) per cent of the length of the truss; at the ordinates 4', 4⁵, approximately seventeen (17%) per cent of the length of the truss; and at the ordinates 4², 4⁴, approximately eighteen (18%) per cent of the length of the truss. These points define points in the top chord and the curvature of said top chord may be determined 105 with sufficient accuracy for usual purposes, by arcs of circles which pass through the 110

ends of the truss end the location points in the ordinates 4, 4' and 4⁵, 4⁶, adjacent to opposite ends of the truss, and the arc of a circle which passes through the location 5 points in the ordinates 4² and 4⁴ and which merges into the arcs which define the curvatures of the end sections of the truss.

The inner ends of the inclined bottom 10 chord sections terminate substantially at the third ordinates from the outer ends of said inclined sections, respectively.

My improved truss also comprises web 15 members 5, 5', 5² and 5³ which connect the inner ends of the inclined bottom chord sections 2, 2', with the top chord at the points therein defined by the intersections therewith of the ordinates 4, 4', and 4⁵, 4⁶, respectively. Said web members also comprise upright members 5⁴ and 5⁵, which connect the inner ends of the bottom chord sections with the top chords and which are substantially coincident with the ordinates 4² and 4⁴, respectively.

The web members also comprise diagonal 25 bracing members 5⁶ and 5⁷, which connect the top and bottom chords at the upper and lower ends, respectively, of the upright web members 5⁴, 5⁵. As shown, said diagonals 5⁶, 5⁷ are rigidly connecting where they cross 30 each other and are connected with the middle of the top chord of an upright member 5⁸.

Excepting for variations in dimensions, 35 the end sections of the truss shown in the drawing and which may be designated, respectively, A¹, A², and which are formed by the ends of the top chord, the inclined end sections of the bottom chord, and the web members 5 to 5⁵, are, respectively, substan-

tially duplicates in all trusses embodying my 40 invention and improvements, but the bracing between the upright members 5⁴ and 5⁵ may be variously modified within the scope of my invention.

I claim:—

1. In a steel truss, the combination of a bowed top chord, a bottom chord comprising end sections which are inwardly and upwardly inclined to the base line of the truss, and an intermediate section which extends 50 parallel with said base line, and web members comprising two inclined members at each end of the truss which connect the inner ends of the inclined bottom chord sections with the top chord, the inner ends of the inclined bottom chord sections terminating substantially at the third ordinates from the outer ends of said sections, respectively, of at least six ordinates projected upwards 55 from points in the base line of the truss which divide it into parts of equal length, and the web members also comprising upright members which connect the top and bottom chord, two of which are substantially coincident with the third ordinates 60 from the ends of the truss, and diagonal bracing members which connect the top and bottom chords at the upper and lower ends, respectively, of adjacent upright members. 65

2. A steel truss as specified in claim 1, 70 in which an upright web member or members connect the diagonal web members at their intersections, with the top chord.

In testimony that I claim the foregoing 75 as my invention, I affix my signature this 11th day of January, 1922.

HALBERT R. BRADLEY.
